APPARATUS FOR BENDING SHEET OR STRIP METAL

Carl Gustaf Leonard Sjölander, Gottenborg,
Sweden

Application January 18, 1932, Serial No. 587,314

13 Claims. (Cl. 153—12)

To form mouldings of different shapes from strip metal in long length which mouldings are frequently used for buildings, furniture and other purposes, or to provide sheet metal with shaped borders it has hitherto been necessary to treat the said metal either in rolling mills, which process was employed especially for transforming strip metal, or to use presses of various kinds, whereby the material, depending upon the more or less complicated shape of its cross-section, must pass through a more or less considerable number of rolls or to be treated by a more or less considerable number of pressing or bending tools and dies, the exchange of which means waste of time and of productive labour, thus increasing the manufacturing costs. Moreover, whatever rolling mills, presses, tools or dies are used, the work to be performed requires intricate devices and demands, owing to the nature of methods employed, considerable time, as the machines in question do not permit to exceed a certain, relatively low speed of operation.

The present invention has for its object to eliminate the disadvantages and inconveniences mentioned and to permit a substantial increase in working speed amounting to a large increase in the speed hitherto found possible, and provides means for gradually feeding the sheet or strip metal to be treated step by step into and between one or more tools having reciprocating movement and intermittently exerting pressure on opposite sides of said metal to form gradually progressing transformation in cross-section of the treated metal.

The accompanying drawings show diagrammatically and by way of example some embodiments of the means suitable for performing the method, wherein:

Fig. 1 is a front view of a suitable press;
Fig. 2 is a vertical elevation of said press, viewed from the right end in Fig. 1;

Fig. 3 is a similar elevation viewed from the left end in Fig. 1, partly in section;

Fig. 4 shows the device for adjusting the tool on a larger scale;

Fig. 4a is another embodiment of said device;

Fig. 5 shows the knee-joint device of the press together with holding devices for the tools on a larger scale, in vertical section;

Fig. 6 shows the feeding means for the metal to be treated together with the tool, in front view;

Fig. 7 shows the holding devices for the tool, on a larger scale, with inserted tools and between them a metal to be treated, all in vertical cross-section;

Fig. 8 shows a sheet metal provided with a shaped border manufactured according to the method in question;

Figs. 9 to 14 are vertical cross-sections through the tools suitable for manufacturing said border; 5

Fig. 15 shows a strip metal treated according to the method;

Figs. 16 to 21 are vertical cross-sections through the tools suitable for manufacturing said moulding; 10

Fig. 22 shows another sheet metal provided with a border of another shape;

Figs. 23 to 30 are vertical cross-sections through the tools suitable for manufacturing said border;

Fig. 31 shows another strip metal formed to 15 shape according to the method, and

Figs. 32 to 37 are vertical cross-sections of the tools suitable for manufacturing said moulding.

The means for embodying the invention described hereinafter and illustrated in the drawings diagrammatically and by way of example comprises a press, tools and feeding means for the metal which operates in the following way: 20

Upon the body 1 of the press as shown in Figs. 1, 2 and 3 a crankshaft 2 fitted with a flywheel 25 3 and driven by means of any kind is turnably journalled in any suitable way. From the crankshaft 2 reciprocating movements are transmitted by means of a connecting rod 4 to a knee joint 7 consisting of two levers 5, 6. The lower lever 30 5 is swingable in a bearing 8 which is designed as an adjustable slide, which by means of a screw device 9 can be lengthwise displaced upon the lower sliding plate 10.

This displacement can be performed by any 35 suitable means, for instance as shown in Figs. 3 and 4 by a plane sliding plate 10 provided with a longitudinal diagonally arranged groove 10a, in which fits a corresponding tongue 8a on the lower plane surface of the bearing 8. When dis-

placing the sliding plate 10 by means of the screw device 9, the bearing 8 will be forced transversely of the plate 10. As a stopping device 10b is provided, the bearing 8 will be prevented from moving in longitudinal direction and perform a 40

transversal movement only, by which the lever 5 will be more or less inclined and the tool support 12 lowered or raised to adjust the tool. 45

According to another embodiment, shown in Fig. 4a, the adjustment of the tool can be effected 50 by means of inclined planes. In this case the sliding plate 10 is tapered and provided with a longitudinal groove 10a, cooperating with the tongue 8a on the inclined lower surface of the bearing 8, which can slide upon the sliding plate 55

10. By a screw device 9 similar to that described before, the tapered sliding surface can be displaced longitudinally in relation to the bearing 8. Also in this case stopping devices 10b will 5 prevent the bearing 8 from moving in longitudinal direction so that it only performs movements in a vertical direction. In Fig. 4a reference numeral 10c designates a bearing for the screw 9.

The upper lever 6 of the knee joint 7 is swingably connected to a slide 11, slidably arranged upon the body 1 and thereupon guided by means of guides or the like. The slide 11 is, according to the embodiment, on its upper portion arranged as a support 12 for the tools, in which support 15 can be inserted one part 14 of the tools, which in the following will be more particularly described. The other part 15 of the tool is placed in a tool holder 13 located on the body 1. This latter part of the tool is secured to the tool holder by means 20 of screw spindles 17 provided with hand wheels 16, which screw spindles also serve for adjusting the tool. The lower part 14 which is without special fixing devices is disposed in a groove or the like provided in the support 12.

25 When rotating the shaft 2, the slide 11 and consequently the support 12 will be reciprocated by means of the connecting rod 4 and the levers 5, 6, the parts 14 and 15 of the tool being alternately moved toward and away from one another, 30 whereby press work is effected upon opposite sides of the metal interposed between the tools.

The metal 18 to be treated, is fed into the press from the right (Figs. 1 and 6) and inserted between the parts 14 and 15 of the tool. According 35 to the embodiment shown, the feeding means consist of four pairs of feed rollers 19, between every two pairs of which one of the sections 24, 25, 26, is placed into which the tool in the present case is divided. Each of these sections 40 consists of a lower part 14 and an upper part 15, the corresponding parts of which co-operate with one another. Obviously, it is not necessary to divide the tool in sections, but it can consist of a single, undivided length; on the other hand it 45 is also possible to arrange two, three or still more sections, if the final shape of the metal should require more intricate tools. Nor is it necessary to interpose feed rollers between every two sections, but the number of those rollers depends 50 upon the type of work to be done in the press.

According to the embodiment shown in the drawings, the lower feed rollers 19 (Figs. 1 and 6) are adjustable in type by means of worm gears, (not shown in the drawings) and driven 55 by the handwheels 20, so that the distance between the lower rollers and the upper ones can easily be adjusted so as to suit different thicknesses of the metal to be treated. It is also possible to arrange similar adjusting devices for the 60 upper rollers, so that either of them may be adjusted, but in the present case only the lower feed rollers are adjustable, whilst the upper rollers are rigidly journaled.

The following arrangements are made in order 65 to obtain the required gradual step by step feeding of the metal 18;

Upon the crank shaft 2 a slotted disc 21 is provided, on which a crank pin 22 is slidably journaled so that its distance from the centre of the 70 crank shaft 2 can be changed. The rotating movement of the crank shaft 2 is transformed into reciprocating movements by means of a connecting rod 23 designed as a gear rack, co-operating with a gear wheel, which by means of a 75 ratchet device or the like actuates a worm gear-

ing (said gear wheel and said worm gearing being not shown in the drawing), in such a way, that the feed rollers 19 connected to the said worm gearing will turn intermittently. By adjusting the crank pin 22 nearer to or farther from the centre of the crank shaft 2, it is possible to moderate the gradual intermittent feeding, so that at each lowering of the support 12 by means of the levers 5, 6, the feed rollers are rotating and thus feeding a more or less long portion of the 10 metal 18.

The movement (the lifting and lowering) of the support 12 and the rotation of the feed rollers 19 are mutually arranged in such a way, that the feed rollers 19 only rotate, when the support 15 is lowering, while their rotation is interrupted, and consequently the feeding of the material will be stopped, as soon as the support is lifted by means of the connecting rod 4 and the co-operating 20 levers 5, 6.

When beginning the press work, the metal 18 is inserted between the feed rollers 19 shown in Fig. 6 nearest the right, whereby the feed rollers, as soon as they are actuated by the connecting rod 22 and the intermediate gearing, will feed 25 as long a portion of the metal between the tool section 24, as the position of the crank pin 22 on the slotted disc 21 permits.

The support 12, actuated by the connecting rod 4, will, due to the rotation of the crank shaft 2, 30 lift and approach the lower part 14 of the tool to the upper part 15, and thereby effect press work upon opposite sides of the metal 18, which has been fed between the tool. During the rotation of the crank shaft 2, the support 12 will by the 35 described means be lowered again, whilst at the same time the feed rollers are actuated so that they feed a further portion of metal into the tool, and upon further rotation of the crank shaft, the new introduced portion of the metal will be subjected to press work by the portion at the 40 entrance end of the tool. At the same time the before-treated portion of the metal will be subjected to press work by a corresponding adjacent portion of the tool. Thus, according to the feeding, all material fed into the press will gradually 45 be treated by different portions of the tool. If these tools are divided into a more or less great number of sections, the feed rollers interposed between two adjacent sections can feed the metal 50 from the preceding section into the next following.

In Fig. 8 of the drawings a sheet metal 18 provided with a pressed or bent border is illustrated and in Figs. 9 to 14 the tools which have proved 55 to be particularly suitable for performing this kind of work are shown in diagrammatic vertical sections. By means of these tools, metal, the size of which is only limited by its own nature and by that of the manufacturing process, can be treated 60 in almost unlimited lengths.

According to the embodiment shown in Figs. 9 to 14, the tool is for practical reasons divided into three sections 24, 25, 26 and the sheet metal 18 is carried on a table not shown in the drawings, 65 which table can be provided with conveying rollers or the like, so as to facilitate feeding. By hand or by automatically working means the sheet 18 is fed to the first pair of feed rollers 19, whereby the sheet can be fixed in a guiding device of any 70 suitable design so as to prevent the sheet from turning aside from the straight line during feeding.

Near the entrance end, at A—A in Fig. 6, the tool section 24 has in vertical cross-section the 75

shape as shown in Fig. 9, which gradually is changing into the shape shown in Fig. 10 (cross section taken at B—B in Fig. 6). If the crank pin 22 is adjusted for feeding for instance portions of 1" length of the material at each stroke of the connecting rod 23, each portion of 1" in length of the tool section 24 will gradually exert pressing work upon corresponding portions of the gradually fed metal 18.

10 In order to facilitate the transformation in shape, a member 27, cylinder or roller shaped, is pivotably journaled in a corresponding groove in the member 14, which latter can be made of cast steel or other inexpensive material, whilst the member 27 and the corresponding co-operating portion of the upper part 15 suitably are made of tool steel, high speed steel or any other material offering high resistance to wear.

After having been subjected to a preliminary transformation during its passage through the first section 24 of the tool, the metal 18 will be fed by means of the second pair of feed rollers 19 into the second section 25, where it is subjected to a further gradually progressing transformation.

25 The shape near the entrance end (at line C—C in Fig. 6) and near the opposite end (at line D—D in Fig. 6) of this second tool section is shown in Figs. 11 and 12 in vertical cross section and the change from one shape into the other is smooth and gradual.

30 During the gradual step by step passage through this section 25, the intermediate tool-member 29 provided with inclined sliding surfaces will exert a pressure upon the vertical portion of the metal 18, and due to the co-operation of the said member 29 with the upper part 15 and the lower part 14 of the tool, the sheet will be transformed gradually into the shape shown in Fig. 12.

The lower part 14 of the second as well as of the third section 26 consists of three prismatic members, all of them being provided with inclined sliding surfaces: The lower part 14 which in the said sections only has to affix the metal 18 to the upper part 15. A prismatic member 30, provided at the bottom of the groove in the support 12, which member by means of its one inclined side and due to the action of a pin 32 actuated by a spring 31, tends to lift the lower part 14 and to approach it to the upper part 15 of the tool. 45 Finally another prismatic member 33 which is slidable upon one vertical wall of the said groove, opposite to that upon which the member 14 can slide. One inclined surface of the said member 33 co-operates with a correspondingly inclined surface on the member 30, whilst the other inclined surface of the member 33 co-operates with the before mentioned member 29.

50 When lifting the support 12, the intermediate member 29 will slide along the inclined surfaces of the upper part 15 and of the prismatic member 33, and will be forced against the metal 18, which thereby gradually will be bent into the shape shown in Fig. 12, whereafter the metal is fed, by means of the third pair of feed rollers 19, into the third section 26 of the tool. This latter section has, near the entrance end (at E—E in Fig. 6), a cross section as shown in Fig. 13, which smoothly and gradually changes into the shape near the opposite end as shown in Fig. 14 (at F—F in Fig. 6).

55 In order to perform the last step, viz.: bending down the diagonally upwards directed portion of the sheet border, the intermediate member 29 co-operates with a member 29a sliding between said member and the part 15. By means

of this member 29a the said border edge is forced downward around a mandrel 34, slidably arranged in the member 29, whilst at the same time the mandrel 34 effects press work upon the vertical portion of the metal 18 imparting to the same the desired S-shape. The nearer the metal is fed to the end of the section 26, the more inclined becomes the border, until, at the very end, it has a strictly vertical position with respect to the main surface of the sheet metal 18.

60 Fig. 15 illustrates another shape, manufactured from strip metal according to the new method. Also in this case the tool consists of three sections 24, 25, 26. Figs. 16 and 17 show the cross section of the first tool section near their ends (at A—A and B—B respectively in Fig. 6). All parts of the tool, subjected to wear, are made of resistant material as for instance: tool steel or high speed steel or the like.

The metal 18 in strips of considerable length 65 is fed in quite the same manner as described before into the tool by means of the feed rollers 19, and will in the first section 24, gradually be brought into the shape shown in Fig. 17. The second section 25 will transform the shape shown in Fig. 18 into the intermediate shape of Fig. 19 and in the third section 26 the metal 18 will be transformed from the shape shown in Fig. 20 into its final shape shown in Fig. 15. The Figs. 16 to 21 are vertical cross sections through the different tool sections 24, 25, 26 at the lines A—A, B—B, C—C, D—D, E—E and F—F of Fig. 6 respectively.

70 According to this embodiment, the tool suitable for the manufacture of the shape shown in Fig. 15, has in the lower part 14 of all sections 24, 25, 26 a V-shaped cross section. In the plane bottom of the V-shaped groove there is provided at suitable intervals a number of bores 35, whilst the operating member 36 is provided with pins 40 37, fitting the said bores and forming guide means for the member 36. Springs 38 are provided in the bores 35, which tend to push the member 36 in an upward direction.

The working portion of the upper part 15 consists of two members 39, 40, the outer inclined surfaces of which fit the V-groove in the lower part 14, and during the reciprocating movements of the support 12 slide in the said groove.

75 In Fig. 22 is shown another design of a shaped border of sheet metal, which can be treated in a tool with gradually changing cross sections as shown in Figs. 23 to 30 (taken at A—A to F—F respectively in Fig. 6). The tool is divided into three sections 24, 25, 26. Fig. 23 shows the vertical cross section of the first tool section 24 near the entrance end, while Fig. 24 represents a cross section taken approximately at the center of said tool section, and Fig. 25 shows the shape of the tool in section taken at B—B in Fig. 6.

80 During the passage through the first tool section 24, the plane sheet metal is gradually transformed into the shape shown in Fig. 25 with the outer edge bent diagonally downwards. Similar to the tool described before in connection with Figs. 9 and 10, also in the present case the tool is provided in the first section with a cylindrical member 27 arranged longitudinally thereof in a corresponding cylindrical groove in the lower part 14, and pivotally disposed in the same, which member will facilitate the gradual bending operations performed in the said section of the tool.

85 Near the inlet and outlet ends the second tool section 25 has the vertical cross sections shown in Figs. 26 and 27 respectively. The dotted line in

Fig. 26 shows the shape of the member 29 at the entrance end.

Figs. 28, 29 and 30 represent vertical cross sections through the third tool section 26, taken 5 near the entrance end, at about half its length and near the outlet end of the tool respectively. Also this tool section is provided with a pivotal cylindrical member 27 provided in the lower part 14, which member 27 co-operates with a similar 10 pivotal cylindrical member 41 arranged in the upper part 15 of this tool section. The said devices 27 and 41 will highly facilitate the bending work to be performed.

For the manufacture of mouldings as shown in 15 Fig. 31, a set of tools can be employed, the vertical cross sections of which are illustrated in Figs. 32 to 37.

The different sections of the tool operate according to the same principle as described before 20 only that in the present instance the last section 26 of the tool, depending upon the shape of the finished strip metal, is somewhat more intricate than the above described tools.

As will be seen from Figs. 36 and 37, which represent diagrammatical cross-sections of the last 25 section of tool 26 near the entrance and outlet respectively (lines E—E and F—F respectively in Fig. 6), the upper part 15 of this section is provided with a cylindrical member 41 intended to 30 perform the rolling operation of one edge of the strip metal 18, for which purpose the member 41 is pivotal in a corresponding groove in the upper part 15. The pivoting motion of the member 41 is effected by the lower part 14 by means of a 35 semi-cylindrical member 42, to which the movement of part 14 is imparted by a number of bolts 42a or the like, inserted in a member 42b affixed to the upper part 15 of the tool. Thereby the member 42 will turn over the edge of the plate around 40 the mandrel 43.

In order to facilitate this operation, the tool section 26 is provided with mandrels 43, 44, around 45 which the edges are rolled in, so that they form uniform, equally round rolls. Those mandrels 45 suitably form integral parts of the member 28 of the preceding tool section 25 and extend between the following adjacent tool parts 14 and 15.

As mentioned above, all parts of the tools subjected to wear are suitably made of tool-steel, 50 high speed steel or like material and are affixed to the corresponding parts 14 and 15 of the tool by means of screws, bolts or the like, provided they are not slidable or pivotal, so that they can easily be changed. The fixing devices are not 55 shown in the drawings, as the design and the use of those parts will be clearly understood by any skilled tool maker.

In the same manner the feeding rolls can be 60 easily changed and replaced by others, the rolling surface of which fits to the shape of the intermediate stages of the metal to be treated.

The above described apparatus for pressing or bending sheet or strip metal gradually, in a step-wise operation is not limited to the embodiments 65 described, the details of which can be subjected to variations without departing from the scope and spirit of the invention. Thus the tool can consist of a single tool with two or more co-operating parts, but it can also consist of a plurality 70 of sections of varying length. Nor is the invention limited to a press of the design as shown and described, but can consist of any suitable construction either upright or horizontal or inclined. 75 The moving tool holder can be placed above the

stationary tool-holder as is generally done in presses of ordinary construction.

Having now described my invention, what I claim as new and desire to secure by Letters Patent is:

1. In a device for shaping sheet metal, the combination of a reciprocating press, feeding means for a sheet, and shaping tools for producing a gradually progressing bending of the sheet along a transverse section with respect to the direction 10 of feeding movement of the sheet, said tools comprising a plurality of sections, each thereof consisting of a plurality of supports and tool members therefor, one of the latter being self-adjustable with respect to its support and adapted to 15 perform a working movement in its self-adjustment by pressure exerted against it during reciprocation of the press.

2. In a device for shaping sheet metal, the combination of a reciprocating press, feeding means 20 for a sheet, and shaping tools for producing a gradually progressing bending of the sheet along a transverse section with respect to the direction of feeding movement of the sheet, said tools, comprising a support, a self-adjustable tool rotatably 25 mounted in the support and provided with a working face, and a reciprocating member movable towards said rotatably mounted tool to cause working movement thereof by pressure exerted against the working face during reciprocation of the member.

3. In a device for shaping sheet metal, the combination of a reciprocating press, feeding means 30 for a sheet, and shaping tools for producing a gradually progressing bending of the sheet 35 along a transverse section with respect to the direction of feeding movement of the sheet, said tools, comprising a stationary support, a self-adjustable tool rotatably mounted in the support and provided with a working face, and a reciprocating member movable towards said rotatably mounted tool to cause working movement thereof by pressure exerted against the working face during reciprocation of the member.

4. In a device for shaping sheet metal, the combination of a reciprocating press, feeding means 45 for a sheet, and shaping tools for producing a gradually progressing bending of the sheet along a transverse section with respect to the direction of feeding movement of the sheet, said tools, comprising supports, and self-adjustable tool members comprising prismatic bodies having inclined 50 surfaces including working faces and being freely mounted in their supports and held in place between working periods by gravity.

5. In a device for shaping sheet metal, the combination of a reciprocating press, feeding means for a sheet, and shaping tools for producing a gradually progressing bending of the sheet along 60 a transverse section with respect to the direction of feeding movement of the sheet, said tools comprising a stationary upper tool support and a reciprocating lower tool support cooperating with the first support, a plurality of tool members in 65 said lower support, a plurality of self-adjustable tool members for said upper tool support adapted to make a working movement in cooperation with the tool members of the reciprocating lower support.

6. In a device for shaping sheet metal, the combination of a reciprocating press, feeding means for a sheet, and shaping tools for producing a gradually progressing bending of the sheet along 70 a transverse section with respect to the direction of feeding movement of the sheet, said tools com- 75

prising a stationary upper tool support and a reciprocating lower tool support cooperating with the first support, a plurality of self-adjustable tool members arranged in the upper tool support, 5 said members comprising prismatic bodies having inclined surfaces including a working face for performing a working movement by pressure from the lower support.

7. In a device for shaping sheet metal, the combination of a reciprocating press, feeding means for a sheet, and shaping tools for producing a gradually progressing bending of the sheet along a transverse section with respect to the direction of feeding movement of the sheet, said tools comprising a stationary upper tool support and a reciprocating lower tool support cooperating with each other, said upper tool support having a plurality of self-adjustable tool members constituting pivotal members journaled in the upper 15 support and provided with a working surface 20 which performs a working movement by pressure from the lower support.

8. In a device for shaping sheet metal, the combination of a reciprocating press, feeding means for a sheet, and shaping tools for producing a gradually progressing bending of the sheet along a transverse section with respect to the direction of feeding movement of the sheet, said tools, including reciprocating and stationary tool supports, prismatic members having inclined surfaces, and being located respectively in the reciprocating tool support and in the stationary tool support, the said prismatic members contacting the sheet and being adapted to transfer working 30 movements to said members in the stationary support.

9. In a device for shaping sheet metal, the combination of a reciprocating press, feeding means for a sheet, and shaping tools for producing a gradually progressing bending of the sheet along a transverse section with respect to the direction of feeding movement of the sheet, said tools comprising reciprocating and stationary tools supports, pivotal members disposed in the stationary 40 support and pressing means cooperating therewith and adapted to impart pressure to the sheet in a direction other than that of the working movement of the reciprocating tool support.

10. In a device of the class described, a stationary tool support provided with shaping tools, a movable tool support, means for moving a sheet, and a plurality of prismatic tool members located in the moving tool support and adapted to

move one another transversely to the feed direction of the sheet and angularly and parallel to the moving direction of the moving tool support when the moving tool support advances towards the sheet and when one of the prismatic members contacts a portion of the stationary shaping tools.

11. In a device for shaping sheet metal, the combination of a reciprocating press, feeding means for a sheet, and shaping tools for producing a gradually progressing bending of the sheet along a transverse section with respect to the direction of feeding movement of the sheet, said tools comprising a reciprocating lower tool support and a knee joint to reciprocate the support, 10 a connecting rod for the said knee joint, the latter carrying the said support and being held in place partly by the gravity of the support and partly by the said connecting rod which is adapted to give the knee joint a reciprocating movement transversely 15 with respect to the direction of the movement of the support, and means for adjusting the working height of the reciprocating tool support, 20 which consists of a slide engaging the lower tongued bearing for the knee joint with a diagonal groove, said tongue engaging the groove to 25 displace the bearing and adjust the inclined position of the lower knee joint lever.

12. In a device of the class described, a reciprocating lower tool support and a knee joint to reciprocate the support, further a connecting rod 25 for the said knee joint, the latter carrying the said support and being held in place partly by the gravity of the support and partly by the said connecting rod which is adapted to give the knee joint a reciprocating movement transversely 30 with respect to the direction of the movement of the support, and means for adjusting the working height of the reciprocating tool support, 35 which consists of a slide engaging the lower tongued bearing for the knee joint with a diagonal groove, said tongue engaging the groove to displace the bearing and adjust the inclined position of the lower knee joint lever.

13. In a device of the class described, a reciprocating lower tool support and a knee joint to reciprocate the support, further a connecting rod for the said knee joint, the latter carrying the said support and being held in place partly by the gravity of the support and partly by the said connecting rod which is adapted to give the knee joint a reciprocating movement transversely 40 with respect to the direction of the movement of the support, and means for adjusting the working height of the reciprocating tool support, 45 which consists of a sliding wedge plate on which the lower bearing of the knee joint rests.
